(57) **CLAIM**

The ornamental design for a cap with a crown portion of lateral two panels, as shown and described.

DESCRIPTION

FIG. 1 is a perspective view of the cap with a crown portion of lateral two panels showing my design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The long dashed broken lines illustrating the visor, button and crown interior of the cap, as well as the unshaded areas within the broken lines and adjacent to the solid lines, define portions of the cap that form no part of the claimed design. The short dashed broken lines depict stitching that forms no part of the claimed design. The long dashed broken lines and short dashed broken lines do not form part of the claimed design.
